UNITED STATES PATENT OFFICE.

GEORGE ERNEST SCHOLES, OF BIRKENHEAD, ENGLAND.

CALORIMETER.

Application filed March 23, 1925. Serial No. 17,830.

To all whom it may concern:

Be it known that GEORGE ERNEST SCHOLES, a subject of the King of Great Britain, residing at Birkenhead, in the county of Chester, England, has invented certain new and useful Improvements in Calorimeters, of which the following is a specification.

This invention relates to calorimeters of the bomb type such as are employed to determine, by combustion, the calorific value of fuel, and the object is to improve this type of calorimeter in respect to;—the closure means, the ignition means, the means for controlling the supply of gas to support combustion, and the shape and general arrangement whereby the maximum temperature of the surrounding liquid is reached in a much shorter time than is usually taken in apparatus of this class.

According to the invention the closure joint is made by a ring of rubber, rubber-compound or the like flexible material housed in a recess, and interposed between a seating on the shell and a seating on the cap, said seatings forming the annular faces of the recess, and the joints between the faces of the ring and the respective seatings being made by the pressure produced with the bomb when the gas is introduced and also when combustion takes place; when the cap has a socket or flange fitting over the spigoted open end of the shell, the one seating is formed on the nose of the said spigot; when the open end of the shell is socketed to take a cap with a spigot, one of the said seatings is formed at the bottom of the socket, and the other is formed on the nose of the spigot carried by the cap; preferably the facings are serrated with concentric V ridges, and a thin cylindrical extension spigot is formed on the spigoted part or on the part in which the recess is formed or on both said parts so as to constitute an inner enclosing wall of the recess and to provide a water seal. The cap and shell are drawn together so as to locate the said seatings at the desired axial distance apart, to bring the annular ends of the ring into contact with the respective seatings, and the ring is so shaped that when the interior of the bomb is subjected to pressure, the annular faces of the ring are forced by the said pressure into jointing contact with the said seatings.

In the preferred form the shell is inverted, the valved gas connection being fitted to the

solid upper end and an inverted cap fitting its lower open end, the closure joint being made as described by a ring interposed between the shell and the cap; the rods which carry the crucibles and the fuse extending upwardly from the inner surface of the cap.

The invention comprises constructional details as herein described and claimed.

I have illustrated my invention in the accompanying drawings, in which:

Fig. 1 is an elevation in longitudinal medial section.

Fig. 2 is an outside elevation.

Fig. 3 is a plan.

Fig. 4 an inverted plan.

Fig. 5 is a plan in section on the line V, V of Fig. 1.

Fig. 6 is a view of the jointing ring to a larger scale.

Fig. 7 is a fragmentary view of the gas ignition valve of Fig. 1, but to a larger scale.

Fig. 8 is a corresponding detail view of the valve spindle and spring.

Figs. 9 and 10 are detail views of the fuse connection thimbles.

Fig. 11 is a fragmentary section to an enlarged scale of the end of the insulated crucible supporting rod, and

Fig. 12 is a section to an enlarged scale showing the recess into which the closure ring is fitted.

Fig. 13 is a corresponding part plan.

Fig. 14 shows the bomb in position in the calorimeter.

Fig. 15 shows a suitable stand for use when charging the apparatus, and

Fig. 16 is an elevation, in medial section, of a modification.

Referring to Figs. 1 to 14:—

A is the body or shell of the bomb which in the preferred form is arranged to be used with the open end and its closing cap B, lowermost, the crucible being carried from the inside of the inverted cap, and the gas valve connection being made at the solid end a⁵, which is uppermost.

In the arrangement illustrated in Figs. 1 to 14, the joint between the cap B and the shell A is made as follows:—

The shell A (see particularly Figs. 12, 13) is provided with a shoulder a¹, the outer periphery of the shell, beyond the shoulder, being screw-threaded as at a² to take the corresponding screw-thread b² formed on the interior of the flange b¹ of the cap B;

beyond the thread a^2 the nose of the shell is reduced in diameter so as to form a flange a^3 , which when the cap is screwed into place extends nearly down to the interior face b^3 of the cap; the face a^4 is preferably serrated so as to form a series of concentric V or the like ridges.

The cap is recessed as shown at b^4 , and the face of this recess, like the face a^4 , is 10 serrated.

The ring C by which the closure is made, is of rubber, rubber compound or the like flexible material, and is preferably of U-shaped cross-section (see Fig. 6) and it is 15 located in the cap, its lower face c^1 resting on the serrated face b^4 , and its cylindrical side c^2 pressing against the interior surface of the flange of the cap; the nose of the inverted shell A is then screwed into the cap until the face of the shoulder a^1 is, by a hand grip pressed home on to the corresponding face of the cap, the cap being conveniently held by hand, or in a fixed stand such as P (see Fig. 15); the serrated 20 facing a^4 then presses on the upper face c^3 of the ring C, compressing the latter to the desired extent between the facings a^4 and b^4 ; the face c^1 and c^3 of the ring C may be slightly inclined to each other as 25 shown in Fig. 6.

Prior to making the joint in the manner described, the interior of the cap is charged with a small quantity of water, such as is usually employed to absorb the acid formed 30 during combustion; this suffices to seal the end of the spigot, and when the interior of the bomb is subjected to the usual pressures experienced some of this water is forced past the nose of the spigot into the recess in 35 which the ring C is located.

No attempt is made to obtain the final jointing pressure by screwing up, the amount of screwing up needed being only just sufficient to cause the engagement of 40 the locating flange; the actual jointing pressure between the jointing surfaces of the ring and the jointing surfaces of the shell and the cap being ensured by the pressure exerted on the interior of the U-shaped 45 ring when the bomb is charged with oxygen.

The ring d^1 in which the crucible D is carried is provided with a split sleeve d^2 which slides in frictional contact on an insulated rod E extending upwardly from the 50 cap C into the body of the bomb, and is clamped by the nut d^3 ; a second parallel but not insulated rod E' is provided, and the fusible element is attached at opposite ends to these respective rods so that a dependent loop thereof is in the crucible, the connection between the ends of the fusible strip and the rods being preferably made by threading the fusible strip through transverse holes or slots e^1 near the tops of the 55 respective rods, contact being ensured by

chamfered sleeves e^2 which are slid on the respective rods so that the ends of the fusible strip F are gripped between the interiors of the sleeves and the respective rods; the cutting edge of the chamfer is used to sever the strip in position from a reel of strip.

At the upper end solid end a^5 of the shell is fitted a valve-controlled oxygen connection G the bore g^1 of which opens into the interior of the bomb through an oblique small bore a^6 ; the connection G is provided with an easily accessible non-return valve g^2 , preferably formed of an annulus of rubber or the like carried on a suitable 80 stem g^3 which is pressed by a spring g^4 so that the annular valve face is pressed into contact with a depending annular valve seating h^1 (carried by the union fitting H) both by this spring and the internal gas pressure.

The bore g^1 is enlarged at g^5 so as to form a shoulder g^6 against which a bell-shaped piece g^7 engages as the valve and spindle is inserted; the bell g^7 is loosely mounted on the valve rod and is retained thereon by the head g^8 of the rod; the spring g^4 is interposed between the bell g^7 and the valve g^2 ; the valve seating h^1 is screwed or otherwise secured into the bore h^2 of the union fitting H, which in turn takes the coned fitting h^3 connected to the oxygen supply and jointed to the fitting H by the nut h^4 . When the valve, the spindle, the spring and the bell are inserted 100 in the bore g^5 of the connection G, the serrated edge of the bell engages with the shoulder g^6 , so that when the union fitting H with the valve seating is screwed into position, the spring g^4 is compressed and exerts an initial closing pressure between the valve and the seating. The valve fitting is thus easily removable for cleaning and inspection.

In order to withdraw the products of combustion, after the test has been made or for estimation and analysis, this can be accomplished after the connection h^4 has been removed, through the valve connection, the valve being opened by the insertion of a rod through the bore h^2 , suitable provision being made to lead the gas to be withdrawn to a suitable container. I prefer however to provide a separate fitting K for this purpose; this fitting is provided with a valve k^1 held against its seating k^2 by the screw-threaded gland k^3 , which, when it is desired to withdraw the products of combustion, is screwed back to permit the gas to pass through an outlet k^4 as required. Leakage is prevented by a rubber or like packing ring k^5 .

The upper portion of the shell is free from any projections and may be provided with a close fitting encircling agitator by 100

the operation of which a ready transfer of heat from the shell to the liquid is ensured, thus reducing the time interval between firing and the attainment of maximum temperature of the water in the calorimeter. The shell and cap are preferably made of stainless steel but ordinary steel suitably plated, or enamelled, or lined with platinum may be employed.

10 The underside of the cap is usually fitted with three insulated supporting legs. In the example illustrated the rod E is flanged as at e^3 and passes through an insulating bush e^4 fitted with insulating washers e^5 and held in place by a metal nut e^6 having a plunger-like extension e^7 pressed outwardly by the spring e^8 , so that when the calorimeter rests on the three feet I fitted with insulators i^1 , the contact e^7 makes electrical contact with the metal of the water calorimeter O (see Fig. 14) so that when one terminal of the battery M is connected to the calorimeter O and the other is connected to the metal body of the bomb, the circuit is completed to the fuse F.

15 In using the appliance the cap B may be conveniently fitted on the fixed stand P, the crucible D containing the substance to be tested and the fuse F being fixed in proper position. A small quantity of water is added to the interior of the cap so as to seal the flange a^3 , and to absorb the acid elements of the products of combustion, and the shell is screwed into place; the apparatus is then placed in the calorimeter O and the electric circuit is made by closing a switch such as m^1 , whereupon combustion takes place, and as the exterior of the calorimeter is practically composed of plane and cylindrical surfaces the heat generated is transferred to the water in the calorimeter in a comparatively short time thus minimizing losses due to radiation, the process being aided by vertical movement imparted to the stirrers o^1 .

20 The invention is applicable to the usual type of bomb calorimeter as shown in Fig. 16, in which the shell A' is used with the open end uppermost, the crucible being carried from the inner and under side of the cap B' by rods E² and E³, the latter of which is insulated from the cap and forms one of the terminals for the electrical attachment.

25 The closure between the body A' and the cap B' is effected substantially as described by means of the ring C' fitted in a recess Q formed between the body and the cap. The bounding outer wall of the recess Q is the inner cylindrical interior portion of the socket a^{10} formed at the open end of the shell A', the end of the socket being screwed as at a^{11} to take the screw threads b^{10} formed on the spigot portion b^{11} of the cap B'. 30 This spigot has a serrated face b^{12} and the

lower part of the recess Q in the socket has a corresponding serrated face a^{12} ; these facings correspond with the facings a^4 and b^4 in the modification first described. Within the facing b^{12} the cap is provided with an extension flange b^{13} which aligns with the flange a^{13} formed on the shell part A'. The ring C' is housed in the recess Q so formed, and in order to moisten the surfaces and flood the recess Q with water a small bore pipe q^1 is fitted, the upper end of which passes through the spigot portion b^{13} , and the lower end of which is carried nearly to the bottom of the shell A' so that some of the water with which the shell is charged is, when the interior is subjected to pressure, forced up through the pipe q^1 into the recess Q.

35 In other respects the bomb illustrated in Fig. 16 may be constructed as described in connection with Figs. 1 to 14 except that the connections H and K are fitted to the cap B' instead of to the solid end of the shell as in the modification first described.

40 The details of construction may be modified and rings of suitable sections other than that illustrated may be employed.

45 What I claim as my invention and desire to secure by Letters Patent is:—

1. In a calorimeter of the bomb type in combination:—an open ended containing shell; a seating formed at the open end of the shell; a cap adapted to close the open end of the shell; a seating formed on the interior surface of the cap; attachment means between the cap and the shell adapted to hold the cap in closed position with the two said seatings in definite relationship; a flexible ring adapted to make contact with the two respective seatings when the cap is in its closing position so that when the interior of the bomb surface is subjected to pressure the ring is pressed onto the seatings; means for admitting gas to the interior of the bomb; means for supporting the substance to be tested; and means for igniting the substance.

2. In a calorimeter of the bomb type in combination:—an open ended containing shell; a seating formed at the open end of the shell; a cap adapted to close the open end of the shell; a seating formed on the interior surface of the cap; attachment means between the cap and the shell adapted when the cap closes the open end of the shell to bring the two said seatings into definite relationship; a flexible ring, the opposite end surfaces of which are adapted to make contact with the respective seatings when the cap is in its closing position; means adapted to prevent the extension of the ring in a radial direction so that when its interior surface is subjected to pressure it expands in an axial direction; means for admitting a gass to the interior of the bomb;

means for supporting the substance to be tested; and means for igniting the said substance.

3. In a calorimeter of the bomb type in combination;—an open ended containing shell; an annular seating formed at the open end of the shell; a cap adapted to close the open end of the shell; an annular seating formed on interior surface of the cap; attachment means between the cap and the shell adapted when the cap closes the open end of the shell to bring the two said seatings to a definite axial distance apart; a flexible ring, the opposite end surfaces of which make contact with the respective annular seatings when the cap is in its closing position; an annular recess formed in the interior surface of the flexible ring; means adapted to prevent the extension of the ring in a radial direction, so that when its interior surface is subjected to pressure it expands in an axial direction; means for admitting gas to the interior of the bomb; means for supporting the substance to be tested; and means for igniting the said substance.

4. In apparatus as claimed in claim 1, the open end of the shell being provided with a recess, the shell seating being located at the end of said recess.

5. In apparatus as claimed in claim 1, the interior surface of the cap having a recess therein, the cap seating being located at the end of said recess.

35 6. In apparatus as claimed in claim 1, the open end of the shell being provided with a recess, the shell seating being located in said recess, the interior surface of the cap being also provided with a recess, the cap seating being located at the end of said last mentioned recess.

7. In apparatus as claimed in claim 1, the open end of the shell being provided with a recess, the shell seating being located in said recess, the interior surface of the cap being also provided with a recess, the cap seating being located at the end of said last mentioned recess, and means connecting the interiors of the said recesses with the lower end of the space enclosed within the calorimeter so that a liquid enclosed within the said space is when pressure is generated within the said space forced into the said recesses.

55 8. In a calorimeter of the bomb type, in combination;—an open ended containing shell; a seating formed at the open end of the shell; a cap adapted to close the open end of the shell said cap being inverted to form a base for the inverted shell; a seating formed on the interior surface of the cap; attachment means between the cap and the shell adapted when the cap closes the open end of the shell to bring the two said seatings into definite axial relationship; a flex-

ible ring the opposite end surfaces of which make contact with the respective seatings when the cap is in its closing position; means adapted to prevent the extension of the ring in a radial direction so that when its interior surface is subjected to pressure it expands in an axial direction; a port formed in the upper closed end of the shell for admitting gas; means carried by the shell for controlling the admission of said gas; means for carrying the substance to be tested; and means for igniting the said substance; both said means being carried from the cap.

9. In a calorimeter as claimed in claim 8, an external screw thread on the open end of the shell, a flange on the cap having a corresponding interior screw thread, a shoulder on the shell against which the end facing of the flange of the cap abuts and so limits the screw-on motion and determines the axial distance apart of the said seatings.

10. In a calorimeter as claimed in claim 8, the inner surface of the flexible ring being provided with an annular recess.

11. In a calorimeter as claimed in claim 8, the interior wall of the recess for the seating in the end of the shell having a flange extending to within a short distance of the interior surface of the cap.

12. In a calorimeter as claimed in claim 8, the diameter of the shell being reduced at the end to form the seating at the open end of the shell, the end of the shell having a flange, extending to within a short distance of the interior surface of the cap, and the surface of which prevents the extension of the flexible ring in a radial direction being on the interior surface of a flanged portion of the cap.

13. In a calorimeter as claimed in claim 8, the seating in the cap at the bottom of an annular recess being formed in the interior surface of the cap.

14. In a calorimeter as claimed in claim 8, the seating for the flexible ring being grooved so as to form a series of circumferential ridges adapted to engage the end surface of the ring.

15. In a calorimeter as claimed in claim 1, means for controlling the admission of the gas for supporting combustion, comprising a valve with an annular face fixed to a valve spindle, a bell shaped fitting adapted to slide on the said spindle, a spring for the valve interposed between the bell shaped fitting and the valve, a bore leading to the interior of the calorimeter, a shoulder in the bore to engage the bell shaped fitting, a screw-threaded part of the bore to take a screwed spigot carrying a valve seating, and a gas connection fitted to the bore of the said seating.

16. In a calorimeter as claimed in claim 8, means for admitting gas to the interior of the bore, comprising a sleeve screwed into

- the closed upper end of the bomb, the bore of the sleeve communicating with the interior of the bore, a valve with an annular face fixed to a valve spindle, a bell shaped fitting adapted to slide on the said spindle, a spring for the valve interposed between the bell shaped fitting and the valve, a screwed spigot carrying the valve seating adapted to screw in the screw-threaded upper end of the bore of the sleeve, and gas connections attached to the said spigot. 25
17. In a calorimeter as claimed in claim 8, means for carrying the substance to be tested and for carrying a fuse wire to ignite the substance, comprising two supporting rods one electrically insulated from and the other electrically connected to the cap, a crucible adjustably carried on one of the said rods, openings in the ends of said rods adapted 30 to take the ends of the fuse wire, and loosely fitting sleeves having chamfered edges and adapted to be slid over the ends of the rods. 35
18. In a calorimeter as claimed in claim 8, the upper end of the inverted shell of the separate valve controlled passage, being provided with an exit for the products of combustion. 40
19. In combination with the elements claimed in claim 17, a metallic vessel adapted to contain water in which the bomb is adapted to be immersed, three insulating feet on the inverted cap adapted to rest on the bottom of the vessel, a spring electrical connection to the insulating rod supporting the crucible adapted to make metallic contact with the vessel, a source of potential one end of which is electrically connected to the bomb and the other end of which is electrically connected to the vessel. 45
20. In combination with the elements claimed in claim 19, a stand adapted to hold the inverted cap and having recesses to take the three feet and the spring connection to the insulated rod. 45

In testimony whereof I set my hand.

GEORGE ERNEST SCHOLES.
